UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A CANDLE PLATE.

Application filed November 18, 1925. Serial No. 15,458. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for Candle Plates, of which the following is a specification, reference being had to the accompanying drawing, forming part thereof.

Fig. 1 is a side elevation showing my new design.

Fig. 2 is a partial plan view showing the ornamentation, it being understood that the remainder is identical.

I claim:

The ornamental design for a candle plate, as shown.

HERMAN ABRAMS.
